UNITED STATES PATENT OFFICE

HARRY A. FOOTHORAP, OF HARRISBURG, PENNSYLVANIA, ASSIGNOR TO ELLIOTT-FISHER COMPANY, A CORPORATION OF DELAWARE

DEBIT AND CREDIT POSTING MACHINE

Original application filed December 31, 1920, Serial No. 434,250. Patent No. 1,505,385. Divided and this application filed May 3, 1924. Serial No. 710,801.

This invention relates to writing adding machines and is a division of my application No. 434,250 for Letters Patent.

The object of the invention is to facilitate the printing of debits and credits in the same column and their separate accumulation in different registers, by providing means whereby the debit and credit registers may be shifted into and out of operative position with respect to the column.

To the accomplishment of this general object and others of subordinate nature, the invention resides in the construction and arrangement of parts to be hereinafter described and illustrated in the accompanying drawings.

In said drawings:

Figure 1 is a front elevation of a writing adding machine equipped with means for shifting the debit and credit registers and the control bar.

Figure 2 is an enlarged view of the mechanism for shifting the registers and control bars.

Figures 3, 4, 5 and 6 are detail sectional views.

Figure 7 is a detail sectional view taken on the line 7-7 of Figure 1.

The machine illustrated is what is known to commerce as the Elliott-Fisher bookkeeping machine which includes a flat platen 1, tracks 2 and a line space frame 4 movable longitudinally of the platen on the tracks. A carriage 6 shown diagrammatically in Fig. 1 supports the printing mechanism of the machine and various ancillary mechanisms including actuating mechanism for the adding devices or registers which constitute usual elements of the ordinary equipment of the machine.

In rear of the carriage 6 the frame 4 is equipped with a register bar 7^a carried by vertical supports 8 rigid with the frame. The bar 7^a supports a series of adding devices or registers 9, 9^a, 10, 11, 12, 13, 13^a and 14. The number and dimensions of the registers is arbitrary. The illustration shows the registers 9 and 9^a mounted in the same frame and 13 and 13^a similarly mounted because these double registers are designed to accumulate

different but related items, as for instance, debits and credits. It is unnecessary to describe these adding devices or registers in detail. Suffice it to say that each includes a series of number wheels occupying progressive denominational positions and having the digits, naught to nine, distributed about their peripheries and displayed one at a time opposite a sight opening. Associated with these wheels is the usual carrying mechanism, whereby, when the limit of value of any denomination is reached by the rotation of the number wheel, the value thus accumulated will be transferred to the wheel of next higher denomination.

So also, the actuating mechanism for these registers being of well known character requires no specific description. It may be stated however that this actuating mechanism includes a master wheel 15, mounted on and laterally movable with the carriage 6 and rotatable by numeral keys, a number of increments corresponding to the value of the digits printed in a given denominational position on the work sheet. As the carriage advances across the column to print the digits included in a number the master wheel is advanced to successive number wheels. Thus, the denominational position of the printing mechanism in the column and the denominational position of the master wheel in the register correspond, so that the amount accumulated by the register corresponds in both numerical and denominational value to the numerical and denominational values of the digits printed in the column.

In addition to the coaction between the master wheel and the registers there is necessarily a coaction between other parts associated with the carriage and frame, respectively, to control certain functions of the adding mechanism. The specific character of these mechanisms is not of moment for the purpose of this disclosure but in order to make the succeeding description clearer attention is called at this point to the fact that in the well known machine a depressor plate 16 is associated with each register for coaction with an arm mounted on the carriage and controlling certain of the operating connec-

tions of the actuating mechanism. Obviously, the plate 16 must bear a definite relation to the register in order to coact with the arm when the register and master wheel are in proper relation. Also, in this connection, attention is directed to the fact that a control bar 17 is appropriately mounted in rear of the carriage for the support of adjustable controlling devices 18 which coact with associated mechanism to control certain phases of the adding operation.

Differently expressed, the register must be appropriate in position to a particular column field or area of the work sheet so that when the printing point of the machine is located in that column position the master wheel will be correspondingly located relatively to the register. Therefore, if the object of this invention is to be attained, that is to say, the printing of certain numbers in a single column and the addition of certain of these numbers in one register and others of said numbers in another register, both of said registers must in some manner be placed in the appropriate relation to the single column. Obviously this can be done in a machine of this type by shifting the two registers alternately into and out of a specified relation to the column. This is accomplished by mounting the register bar 7^a for longitudinal movement by passing the reduced ends 49 thereof through bearings 50 and by providing the same beyond the bearings with stop collars 51 and 52.

35 The register bar is locked in one position by a catch 53 pivoted on the collar 52 and engaging a stud 54 on one of the bearings 50. The opposite end of the catch 53, which is in the form of a lever, is provided with an inclined slot 55 engaged by pin 56 projected from an extension 57 located midway of what may be termed a register shifting lever 58, having an operating key 59 at one end and fulcrumed at its opposite end, as indicated 40 at 60, to one extremity of a rigid guide bar 61. To return the lever 58 to normal position when it has been moved therefrom and released, I provide a retracting spring 62, as shown.

50 Disposed longitudinally of the lever 58 is a slot 63 having an offset lower end 64 to receive a pin 65 projecting from the adjacent stop collar 52 of the bar 7^a. It will now be seen that pressure upon the key 59 will swing 55 the lever 58, first causing the pin 56 to swing the catch 53 to its disengaged position. The necessary lost motion of the lever 58 to accomplish this unlocking of the register bar is accommodated by the play of the pin 65 in the offset portion of the slot 63. The pin 65 is then engaged and continued movement of the lever 58 will shift the register bar longitudinally for the purpose of moving the whole series of registers to displace one register from a given column position and to

place the next adjacent register in appropriate relation to such column. Obviously those elements of the control which bear a fixed relation to the registers in the operation of the machine must maintain such relation at all times. Therefore, as the registers are shifted, provision must be made for shifting the control elements with them. To accomplish this object the control bar 17 is in this form of the invention mounted in control bar brackets 66 pendent from the register bar 7^a 75 and movable therewith, the lower ends of these brackets being guided upon the guide bar 61, as clearly shown in Figs. 2 and 3. Each of the brackets 66 is provided with a control bar head 67, having a shank 68 threaded through the bracket and secured by nuts 69. The heads retain adjustable control bar carriers 70, adjustable in different directions and directly carrying the control bar 17. The connection between the bar 17 and one of the carriers is effected by a sliding pin 71 fixed to the bar and engaging the carrier, as shown in Figs. 3 and 4, while the carrier associated with the other bracket receives the threaded end 72 of the control bar, which is equipped with an adjusting nut 73 by which endwise adjustment of the bar may be secured, its retention in such position being assured by lock nuts 74.

It will thus be seen that the simple operation of the key, after the printing and adding of debits, for instance, will shift the registers and controls so that when credits or other distinguished items are printed in the same column they will be accumulated in a different register.

What I claim is:

1. In combination a platen, a computing unit including a debit register and a credit register, and means for shifting said unit in opposite directions to present either register in position to be operated as debits or credits are recorded in the column and to displace the other register from such operative position.

2. In combination, a platen, debit and credit registers for accumulating debits and credits, a key for shifting both registers as a unit, relatively to the platen, to bring one register to the column position and to displace the other from the column position, and actuating mechanism arranged to actuate the register located in column position.

3. In a machine of the character described, the combination with a platen, of a plurality of registers, controlling mechanism including a controlling bar bearing fixed relation to the registers, and means for shifting the registers and control bar relatively to the platen and for retaining the same in the new relation.

4. In a machine of the character described, the combination with a platen, a plurality of relatively stationary registers, and means including a key operative to shift the registers relatively to the platen.

5. In a machine of the character described, the combination with a platen, a plurality of relatively stationary registers, controlling mechanism, and means including a key for shifting the registers and the controlling mechanism relatively to the platen.

6. In a machine of the character described, the combination with a platen, a plurality of registers, controlling mechanism including a control bar, a key operative to shift the registers and control bar relatively to the platen, and means for retaining the registers and control bar in the new position.

7. In a machine of the character described, the combination with a platen, of a plurality of relatively stationary registers, controlling mechanism including a control bar, means connecting the registers and control bar for movement together relatively to the platen, and a key operative to shift the registers and control bar.

8. In a machine of the character described, the combination with a platen, of a plurality of relatively stationary registers, a controlling mechanism including a control bar, means connecting the registers and control bar for movement together relatively to the platen, a key operative to shift the registers and control bar, and a latch for retaining the registers and control bar in position.

9. In a writing computing machine including a platen, an accumulating unit including a debit and a credit register and shiftable to operatively position either register to accumulate numbers as they are printed in a single column, and means for shifting said unit.

10. In combination, a platen, a series of computing units for use in accumulating different columns of numbers respectively, said units including a plurality of registers, and means for shifting in opposite directions a unit including two registers to present said registers alternately in a single column position.

In testimony whereof I hereunto affix my signature.

HARRY A. FOOTHORAP.
